Primary Examiner — Mark A Goodwin(74) *Attorney, Agent, or Firm* — HULSEY P.C.(57) **CLAIM**

The ornamental design for a lawn mower shroud openings, as shown and described.

DESCRIPTION

FIG. 1 is a perspective view of lawn mower shroud openings showing my new design;

FIG. 2 is a front elevational operational view of FIG. 1;

FIG. 3 is a rear elevational view of FIG. 1;

FIG. 4 is a right elevational view of FIG. 1;

FIG. 5 is a left side elevational view of FIG. 1;

FIG. 6 is a top plan view of FIG. 1;

FIG. 7 is a bottom plan view of FIG. 1; and,

FIG. 8 is an operational view of FIG. 1.

The broken lines in the drawings depict portions of lawn mower shroud openings that form no part of the claimed design.
